UNITED STATES PATENT OFFICE.

STANLEY H. BARNES, OF MOUNT VERNON, NEW YORK, ASSIGNOR TO GLEASON-TIEBOUT GLASS COMPANY, OF BROOKLYN, NEW YORK, A CORPORATION OF NEW YORK.

DESIGN FOR A GLASS LIGHTING GLOBE.

Application filed February 10, 1926. Serial No. 16,482. Term of patent 3½ years.

To all whom it may concern:

Be it known that I, STANLEY H. BARNES, a citizen of the United States, residing in Mount Vernon, in the county of Westchester and State of New York, have invented a certain new, original, and ornamental Design for Glass Lighting Globes, of which the following is a specification, reference being had to the accompanying drawings, forming

ing a part thereof, and of which Figure 1 is a perspective view, and Fig. 2 is a fragmentary sectional view of a glass lighting globe showing my new design.

I claim:

The ornamental design for a glass lighting globe as shown.

STANLEY H. BARNES.
